UNITED STATES PATENT OFFICE.

EVERETT R. BURTNELL, OF LOS ANGELES, CALIFORNIA, ASSIGNOR, BY DIRECT AND MESNE ASSIGNMENTS, TO THE AUTOMOTIVE VALVES CORPORATION, OF RENO, NEVADA, A CORPORATION OF NEVADA.

INTERNAL-COMBUSTION ENGINE.

Application filed April 20, 1926. Serial No. 103,288.

My invention relates to internal combustion engines, and particularly to a cylinder head for sleeve valve engines, in which inlet and exhaust ports are arranged to establish 5 port and passage communication with the combustion chamber at the head end.

The principal object being to provide a cylinder head adapted to be applied to the engine, in a position which will permit the 10 sleeve valve reciprocating over the cylinder head, in a telescoping manner and to form the cylinder head with an inlet passage and exhaust recesses, which will accomplish fresh charge stratification, efficient scaveng- 15 ing of the residual products of combustion from the combustion chamber and localization of a sufficient quantity of fresh gaseous mixture, adjacent to the spark plug, to obtain uniform and regular combustion, when 20 the engine is operated at light load or heavy load.

With the foregoing, and other objects in view, my invention consists in certain novel features of construction and arrangement of 25 parts that will be hereinafter more fully described and claimed and illustrated in the accompanying drawings in which:

Fig. 1 is a vertical section taken through the center of the combustion chamber of a 30 sleeve valve engine showing the cylinder head of my improved construction, the plane of the cutting edge intersecting the two oppositely disposed exhaust recesses.

Fig. 2 is a vertical section taken through 35 the center of the combustion cylinder with the plane of the cutting edge taken at right angle to the plane of the cutting edge as illustrated in Fig. 1.

Fig. 3 is a horizontal section taken on line 40 3-3 of Fig. 1.

Referring by numerals to the accompanying drawings which illustrate a practical embodiment of my invention, 10 designates a cylinder, a sleeve valve 11 is arranged for 45 slidable movement within the cylinder, a piston 12 is arranged for reciprocatory movement within the sleeve valve, and a cylinder head 13 is arranged as a depending member, adapted to fit within the bore of the sleeve 50 valve, inlet ports 14, are formed at two points of the sleeve valve, in diametrically opposite position. Exhaust ports 15 are formed in the sleeve valve in diametrically opposite in

position, the inlet and exhaust ports occupying substantially the same plane, the said 55 plane of the ports being at right angle to the axis of the sleeve valve.

A traverse passage 16 is formed through the crankward end of the cylinder head and the cylinder head is arranged in a position 60 relative to the location of the inlet ports, formed in the sleeve valve, which will facilitate the registration of the inlet ports formed in the sleeve valve, with the said traverse passage formed in the cylinder head, at a 65 time such port and passage registration is desired.

Exhaust recesses 17 are formed in the periphery of the cylinder head, at the extreme end of the said cylinder head and in 70 substantially the same plane as the plane of the traverse passage 16. The exhaust recesses are located in the cylinder head in a position which will facilitate the registration, of the exhaust ports 15, with the said 75 recesses at the desired time relative to the stroke movement of the piston 12, and the movement of the sleeve valve 11. An outlet venturi formed throat 18 is formed through the end of the cylinder head, establishing 80 passage communication between the piston sweep chamber 19 and the traverse passage 16.

The traverse passage 16 provides a fresh 85 charge admission duct, between the inlet ports 14 of the sleeve valve and the piston sweep chamber, and a spark plug 20 is provided and secured in the cylinder head in a position, which will enable the sparking terminals to protrude into the said traverse 90 passage in the cylinder head.

The volume movement through and about the cylinder head is described as follows:

Assuming the piston 12 is at crankward 95 dead center, the sleeve valve 11 will be approximately in the position of crank end dead center, the exhaust ports 15 will be open to the combustion chamber, the residual gases will be exiting therefrom, through the recesses 17 formed in the crank end of the cylinder head, the inlet ports 14 of the sleeve valve will be open to the transverse passage 16, a precompressed fresh 100 charge of gaseous mixture will be passing in column movement, through the said inlet ports of the sleeve valve, through the 105

transverse passage 16 of the cylinder head, the two columns engaging at the center of the transverse passage the inlet charge will be diverted crankwardly, passing into the 5 piston sweep chamber through the venturi formed throat 18, formed in the end and center of the cylinder head.

The velocity of the fresh charge being inducted, will direct the charge to the crankward end of the piston sweep chamber, at which point it will engage the piston head, a scavenging action of the piston sweep chamber of residual products of combustion will be the result. When the chamber has 15 been scavenged and at a time the piston within the sleeve valve has passed crank end dead center, the exhaust and inlet ports will be cut off of registration with the chamber and compression of the fresh 20 charge inducted, will take place within the chamber by the headward movement of the piston.

It will be seen that I have provided a practical means of accomplishing stratified 25 fresh charge induction into a combustion chamber during the exhaust period, providing means of efficiently scavenging the residual products of combustion thereby and establishing an undiluted gaseous mixture adjacent the spark plug, which will enable the 30 engine to be operated with the desired flexibility.

It will be understood that minor changes in the size, form and construction of the 35 various parts of my improved construction may be made and substituted for those herein shown and described without departing from the spirit of the invention, the scope of which is set forth in the appended 40 claims.

I claim as my invention:

1. In an internal combustion engine, a sleeve valve, a depending cylinder head,

a transverse passage in the abutment of the said cylinder head, the said transverse 45 passage extending centrally through the said head with openings through the periphery of the said head at oppositely disposed points, two oppositely disposed recesses formed at the end edge of the abutment of the cylinder head, the said recess being in substantially the same plane as the plane of the said transverse passage, the said recesses being formed at points equally disposed circumferentially between the said openings of the 50 transverse passage through the periphery of the said cylinder head; a venturi formed throat formed at the center of the said cylinder head, said throat providing a central opening crankwardly from the said transverse passage, the roof of the said recesses being formed as a semi-circular contour extending headwardly and radially, and ignition means located in the cylinder head with the sparking terminals extending into the 55 transverse passage in the said cylinder head.

2. A depending cylinder head for sleeve valve type internal combustion engines, a transverse fresh charge inlet passage formed in the said cylinder head, inlet openings of 70 the said transverse passage formed through the periphery of the said cylinder head at each end of the said transverse passage; an outlet opening of the said transverse passage formed in the end of the said cylinder 75 head, recesses formed in the end edge of the said cylinder head for the deflection of the residual gases within the chamber enclosed by the said cylinder head, and ignition means located in the cylinder head, the sparking terminals of which protrude into the said transverse charge inlet passage.

In testimony whereof, I hereto affix my signature.

EVERETT R. BURTNELL.
